UNITED STATES PATENT OFFICE.

MAYNARD F. MACDONALD, OF VICTORIA, BRITISH COLUMBIA, CANADA, ASSIGNOR TO
HARRY R. MITCHELL, OF SEATTLE, WASHINGTON.

SPARK PLUG.

Application filed May 1, 1924. Serial No. 710,408.

To all whom it may concern:

Be it known that I, MAYNARD F. MACDONALD, a citizen of the United States, residing at 1449 Fort Street, Victoria, British Columbia, Canada, have invented certain new and useful Improvements in Spark Plugs, of which the following is a specification, reference being had therein to the accompanying drawings.

10 This invention relates to spark plugs for internal combustion engines and it has for its object to provide an improved device of this character constructed in such manner as to insure a hot spark at all times and to 15 prevent the fouling of the plug by the accumulation of carbon deposits thereon. The means by which these objects are obtained are illustrated in the accompanying drawing, wherein—

20 Fig. 1 is a side elevation of a spark plug constructed in accordance with the invention;

Fig. 2 is a vertical sectional view therethrough;

25 Fig. 3 is an under side view; and

Fig. 4 is a horizontal sectional view upon line 4—4 of Fig. 1.

Like numerals designate corresponding parts in all of the figures of the drawing.

30 Referring to the drawing 5 designates the shell of the plug which is externally threaded at 6 to adapt it to be screwed into an engine cylinder and internally threaded at 7 for the reception of the packing gland 8.

35 This packing gland serves a function common in devices of this character: viz; that of holding an insulating porcelain 9 in place by pressing a shoulder 10 of said porcelain against a shoulder 11 of the shell,

40 suitable packing washers 13 and 14 being employed in a usual and well known way. At its lower end the shell 5 is provided with

an apron 15 having a plurality of openings 16 formed in its side wall. The positive

45 electrode consisting of a wire or rod 17 extends through the porcelain 9 in the usual way but this electrode differs from the electrodes ordinarily employed in that at its lower end it is provided with a ball 18 and

50 the spark takes place between the periphery of this ball and the rim or lower edge portion of the apron 15. The gap across which the spark jumps consists of the annular opening 20 between the periphery of the

55 ball and the lower end portion of the apron

15. The ball is larger in diameter than the opening 21 formed in the lower end of the porcelain 9 and thus this ball constitutes a barrier to prevent the passage of carbon and oil deposits upwardly into said opening 21. Furthermore the rounded lower face of the ball tends to deflect the gases, either under compression or under the force of explosion, outwardly, as indicated by the arrows in Fig. 2 and these gases and any particles of carbon or oil entrained therein may pass outwardly through the openings 16. It will be observed that the openings 16 are of considerable size, thus the combined area of these openings is materially 65 in excess of the area of the spark gap formed by the annular opening 20. Consequently a free circulation of the gases may be maintained through the spark gap. The passage of the gases through the annular 70 space 20 keeps this space clean and free of carbon and thus prevents short circuiting of the plug. At the same time the presence of the openings 16 insures that such carbon and oil deposits as may be blown out of the 75 annular space 20 will not find their way up into the body of the plug and accumulate there to constitute a source of trouble. The under side of the ball presents a flaring surface and the upper edges of the 80 openings 16 are outwardly flaring, as indicated at 16^a. This causes the current of air to travel, as before stated, in the direction indicated by the arrows in Fig. 2, and exerts such scouring action over the confronting faces of the ball and the inner edge of the rim of the apron as to maintain these parts bright and clean and in such condition as will insure the ready passage of the 85 spark between them.

90 It is to be understood that the invention is not limited to the precise construction set forth but that it includes within its purview whatever changes fairly come within either the terms or the spirit of the appended 95 claims.

Having described my invention, what I claim is:

1. A spark plug comprising an externally threaded shell, a gland threaded into the 105 upper end of said shell, a porcelain held in place within the shell by said gland, an electrode carried by said porcelain comprising a rod passing therethrough and a ball upon the lower end of said rod, the lower 110

end of the shell being provided with a depending apron having openings formed through its sidewalls which openings lie above the center of the ball, that portion 5 of the apron below said openings lying substantially opposite the center of the ball and the lower portion of the ball projecting materially below the lower edge of the apron, said openings having flaring upper 10 edges which in conjunction with the flaring lower face of the ball direct the gases passing through the annular space between the ball and the lower edge of the apron, upwardly and outwardly.

15 2. A structure as recited in claim 1 wherein the lower end of the porcelain is provided with an opening, said ball being materially larger in diameter than the opening in the porcelain.

20 3. A spark plug comprising an externally threaded shell, a porcelain supported therein, an electrode carried by said porcelain comprising a ball located at the lower end of said porcelain, the lower end of the shell 25 being provided with a depending apron having openings formed through its side walls, which openings lie above the center of the ball, that portion of the apron below said openings lying substantially opposite 30 the center of the ball and the lower portion of the ball projecting materially below the

lower edge of the apron, said opening having flaring upper edges which, in conjunction with the flaring lower face of the ball, direct the gases passing through the annular space between the ball and the lower edge of the apron, upwardly and outwardly. 35

4. A spark plug comprising a shell and a body of insulating material held therein, a positive electrode carried by said body of insulating material, a substantially straight side apron open at its bottom, substantially over its whole diameter, carried by the shell, said positive electrode having an enlarged 40 lower end which is directly opposed to and co-acts with the lower inner portion of the shell to form a spark gap, there being several uniformly spaced openings formed in the side walls of the apron materially above 45 the spark gap, the area of the openings with respect to the area of the spark gap being such that gases forced through the open bottom of the shell may pass freely through the space between the said electrode and the lower inner edge of the apron and be discharged uniformly at all points in the circumference of the latter. 50

In testimony whereof I hereunto affix my signature.

MAYNARD F. MACDONALD.
